(57) **CLAIM**

The ornamental design for a power supply for electronic atomizing device, as shown and described.

DESCRIPTION

FIG. 1 is a perspective view of a power supply for an electronic atomizing device according to an embodiment of my design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a power supply for an electronic atomizing device according to another embodiment of my design;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a perspective view of a power supply for an electronic atomizing device according to further another embodiment of my design;

FIG. 18 is another perspective view thereof;

FIG. 19 is a front elevational view thereof;

FIG. 20 is a rear elevational view thereof;

FIG. 21 is a left side elevational view thereof;

FIG. 22 is a right side elevational view thereof;

(Continued)

FIG. 23 is a top plan view thereof; and,
 FIG. 24 is a bottom plan view thereof.
 The broken lines in the drawings depict portions of the
 power supply for electronic atomizing device that form no
 part of the claimed design.
